WEATHERPROOFING OF WALLS

Harry S. Smith, Mineola, N. Y.

Application January 25, 1935, Serial No. 3,387

7 Claims. (Cl. 72—127)

This invention relates to weatherproofing of walls, and more particularly relates to the weatherproofing of walls constructed of brick, or other block material.

5 Heretofore many expedients have been employed to prevent dampness and moisture from penetrating to the inside face of a brick wall and to a finish applied thereto. One expedient has been to construct the wall to a greater depth than 10 is required for structural soundness. Other expedients have included the application of plastic weatherproofing material, lathing and furring on the interior face of the wall. All these expedients have required additional material, labor and time, 15 and accordingly have increased the cost of the construction.

One of the principal objects of this invention is to provide weatherproofing for walls, and particularly for walls constructed of brick or other 20 block material, which effectively prevents moisture and dampness from penetrating to the inner face of the wall from the exterior thereof, and thereby eliminates the necessity of increasing the width of the wall for this purpose, and eliminates 25 the necessity of applying damp-proofing material, furring, and the like to the inner face of the wall for damp-proofing purposes.

Another object of this invention is to provide in 30 a wall constructed of brick or other block material a continuous vented membrane weatherproofing which consists of inexpensive materials, is inexpensive to incorporate in the wall, and which does not weaken or detract from the structural strength or construction of the wall, and which 35 permits the bricks or other block material to be laid in the customary manner.

A further object of this invention is to provide 40 simple and inexpensive vent members for the continuous vented membrane weatherproofing, and vent members which may be inserted inexpensively and conveniently without requiring special chipping or cutting of the bricks or other block material.

Other objects of this invention will be in part 45 obvious and in part pointed out hereinafter.

In order that a clearer understanding of this invention may be had, attention is hereby directed to the accompanying drawing forming a 50 part of this application and illustrating certain possible embodiments of this invention and in which:

Fig. 1 is a horizontal sectional view of a section of a wall provided with weatherproofing embodying this invention;

55 Fig. 2 is a front view thereof;

Fig. 3 is a vertical sectional view thereof and is taken on the line 4—4 of Fig. 2; and

Fig. 4 is a view similar to Fig. 3 but showing a narrower wall.

Similar reference characters refer to similar parts throughout the several views of the drawing.

Referring to the drawing, the wall has a suitable foundation 1 and the bricks of the wall are laid in the usual manner, including header bricks 9 laid in header courses at the usual intervals, and other bricks 2 laid in the usual way. The weatherproofing comprises suitable damp-proof and 10 waterproof material 6, which may be suitable fabric impregnated with asphalt or wax sufficient 15 to render the fabric impervious to water and dampness or may be good quality rubberoid or tar paper, which extends the length of the wall and from a level of the foundation or other drainage level to the top of the wall in a continuous 20 fashion. As shown, this material may comprise a plurality of strips, one above the other. The top strip extends from the top of the wall behind the front header course, then under this header course to the rear of the outer face bricks and 25 downwardly behind these face bricks to the next lower header course, and then forwardly along the top of this header course to the outer face or facade of the wall. The top edge of the next lower strip of damp-proofing material overlaps the rear 30 of the previous strip just above the header and thence extends rearwardly across the top of this header, then downwardly behind the header, then forwardly under the header to the rear of the outer course of bricks below this header, then 35 downwardly behind these bricks to the top of the lowest header course and outwardly along the top of this header course to the outer face or facade of the wall. Another strip of damp-proof material overlaps the rear of this damp-proofing 40 material above the header course and extends rearwardly along the header course and then downwardly behind this header course to the foundation or other drainage level. Thus it will be seen that the waterproofing material is coextensive with the height and length of the wall and there is no opening or break in the material through which water or other moisture can penetrate. The overlapping of the sheets 6 are indicated at 8.

The moisture-proofing material 6 is spaced rearwardly from the face bricks 2 and from the header bricks 9 and is also spaced from the under surface of the header bricks, and these spaces are left clear. These spaces are open to the exterior 55

of the wall through duct members 7 inserted in the horizontal joints 10 immediately above each header course and spaced suitable distances apart, such as six to eight feet. The spaces intermediate 5 ate the face and header bricks and the moisture-proofing material 6 are further vented to the exterior of the wall by apertures 11 formed through the vertical mortar joints at suitable places and 10 preferably meeting the spaces in the vicinity of the under side of the header courses, and being inclined downwardly to the facade of the wall sufficiently to prevent rain from passing rearwardly therethrough. The duct members 7 and the vent apertures 11 are preferably in vertical 15 alignment.

The vent members 7 may be of suitable material, such as galvanized iron, copper, or the like, and of inverted channel form, preferably wider at the rear where they open into the spaces in 20 front of the damp-proofing material 6 than at the facade of the wall where they open into the atmosphere. For instance, these vent members may be three-eighths of an inch in height, one inch wide at the front and three inches wide at 25 the rear. The drain channels of these members should be clear of mortar droppings.

The inclined vent apertures 11 may be formed conveniently by inserting a removable core, such as a nail or spike of appropriate diameter, in the 30 mortar when it is applied, and then withdrawing the core after the mortar has set. Apertures of one-quarter of an inch in diameter have been found to be satisfactory. The mortar makes a very tight and structurally sound bond through 35 the moisture-proofing material over the rear portion of the header courses, and the wall having this weather-proofing is structurally sound in every respect.

In a wall having a thickness of only two courses, 40 as shown in Fig. 4, if it is desired to have the inside face thereof even and straight, for plastering or for other reasons, the rear ends of the header bricks 9 may be chipped slightly, as at 12, the damp-proofing material 6 placed thereagainst, 45 and mortar applied, as at 13, to come flush with the face of the wall.

By reason of the effectiveness of the weather-proofing, it is unnecessary for the prevention of objectionable percolation or transmission of 50 moisture through the wall, to construct the wall of any greater thickness than is necessary for structural strength.

Thus it will be apparent that any moisture reaching the spaces in front of the moisture-proof 55 membrane 6 will not only be prevented from contacting any part of the construction in the rear thereof, but also, on sufficient accumulation, will drain down and through the vent members 7 and will be discharged on the outer face of the 60 wall, and in addition, due to the vent channels of members 7 and the vent apertures 11 air will circulate through the spaces and not only dry any moisture there may be therein but will also dry the facade bricks from the rear, including the 65 rear half of the under surfaces of the header bricks. This tends to prevent efflorescence forming on the bricks, and quickens the drying out of the wall. Preferably the waterproof membrane is disposed behind the facade bricks so as to arrest 70 penetration of moisture as near as possible to its point of ingress.

The header courses have the front half of the under surface and the rear half of the upper surface tied into the wall by mortar.

75 As many changes could be made in the above

construction, and as many apparently widely different embodiments of this invention could be made without departing from the scope thereof, it is understood that all matter contained in the above description or shown in the accompanying drawing be interpreted as illustrative and not in a limiting sense. 5

What I claim is:

1. In a wall comprising a plurality of vertical courses of bricks, including header bricks, of a continuous moisture-proof membrane disposed and extending horizontally and vertically intermediate two of said courses and embracing the rear portion of the upper surface, the rear face and the rear portion of the lower surface of the 15 header bricks, said membrane being separated by a clear space from the adjacent course which is toward the exterior of the wall and from the rear and under surface of the header bricks, drain ducts of inverted channel shape disposed on the 20 forward portion of the header bricks and entirely forward of said membrane and having their channels extending from said space to the exterior of the wall, and air vents in said wall open at the exterior thereof and extending to said space. 25

2. In a wall comprising a plurality of vertical courses of bricks, including header bricks, of a continuous moisture-proof membrane disposed and extending horizontally and vertically intermediate two of said courses and embracing the 30 rear portion of the upper surface, the rear face and the rear portion of the lower surface of the header bricks, said membrane being separated by a clear space from the adjacent course which is toward the exterior of the wall and from the rear 35 and under surface of the header bricks, drain ducts of inverted channel shape disposed on the forward portion of the header bricks and entirely forward of said membrane and having their channels extending from said space to the exterior of the wall, and air vents in said wall open at the exterior thereof and extending to said space, a course of mortar intermediate the front portion of the lower surface of the header bricks 40 and adjacent bricks of a course tying the header 45 bricks into said course, and a course of mortar between the membrane portion disposed on the rear portion of the upper surface of the header bricks and adjacent bricks of another course tying 50 said courses together. 50

3. In a wall comprising a plurality of vertical courses of bricks, including two interlapping horizontal courses of header bricks, of a moisture-proof membrane disposed intermediate two vertical courses and extending continuously horizontally and vertically between said courses and having its lower edge portion lying on the front portion of a horizontal header course and extending to the exterior of the wall, said membrane above said edge portion being separated by a clear 60 space from the vertical course which is toward the exterior of the wall. 60

4. In a wall comprising a plurality of vertical courses of bricks, including two interlapping horizontal courses of header bricks, of a moisture-proof membrane disposed intermediate two vertical courses and extending continuously horizontally and vertically between said courses and having its lower edge portion lying on the front portion of a horizontal header course and extending to the exterior of the wall, said membrane above said edge portion being separated by a clear space from the vertical course which is toward the exterior of the wall, drain ducts of inverted channel shape disposed on said lower edge 70 75 80 85 90 95 98

portion of the membrane and extending from said space to the exterior of the wall, and air vents in said wall open on the exterior thereof and opening into the upper region of said space.

5 5. In a wall comprising a plurality of vertical courses of bricks, including two interlapping horizontal courses of header bricks, of a moisture-proof membrane having its upper edge portion embracing a rear portion of the upper surface, the
10 rear face, and a rear portion of the lower surface of one of said header courses and having its lower edge portion lying on the front portion of the upper surface of the next lower header course and extending to the front face thereof, and the
15 intermediate portion of said membrane being disposed and extending continuously horizontally and vertically between two vertical courses, said membrane being separated by a clear space from the rear face and under surface of the upper
20 header course and from the vertical course which is toward the exterior of the wall, means, including ducts of inverted channel shape disposed on said lower edge portion of the membrane, for draining said space, and means, including air
25 vents in said wall, for ventilating said space.

6. In a wall comprising a plurality of vertical courses of bricks, including two interlapping horizontal courses of header bricks, of a moisture-proof membrane having its upper edge portion
30 embracing a rear portion of the upper surface, the rear face, and a rear portion of the lower surface of one of said header courses and having its lower edge portion lying on the front portion of the upper surface of the next lower header
35 course and extending to the front face thereof, and the intermediate portion of said membrane

being disposed and extending continuously horizontally and vertically between two vertical courses, said membrane being separated by a clear space from the rear face and under surface of the upper header course and from the vertical
5 course which is toward the exterior of the wall, means, including ducts of inverted channel shape disposed on said lower edge portion of the membrane, for draining said space, and means, including air vents in said wall, for ventilating said
10 space, a course of mortar engaging the front portion of the lower surface of one of said horizontal header courses and engaging an outwardly disposed vertical course, and a course of mortar engaging the portion of said membrane on the
15 rear portion of the upper surface thereof and engaging the next inward vertical course, whereby said header course is tied into both said vertical courses and said vertical courses are tied together.

20 7. In a wall of the character described, two adjacent vertical courses of bricks including horizontal overlapping header courses tying said courses together, a continuous moisture-proof membrane disposed and extending horizontally
25 and vertically between said courses and between the overlapping header courses, the forward vertical course and the forward header bricks being spaced forwardly of said membrane, providing a free air and drain space covering the entire rear
30 surfaces of said vertical course and header bricks, and drain ducts disposed on the forward portions of the forward header bricks, entirely forward of said membrane to drain moisture from said space to the exterior of the wall.

35 HARRY S. SMITH.
